(57) **CLAIM**

The ornamental design for a wall panel for an animal housing unit, as shown and described.

DESCRIPTION

FIG. 1 is a top front perspective view of a wall panel for an animal housing unit according to my invention;

FIG. 2 is a bottom rear perspective view of the wall panel of FIG. 1;

FIG. 3 is a right side elevation view of the wall panel of FIG. 1;

FIG. 4 is a front elevation view of the wall panel of FIG. 1; FIG. 5 is a left side elevation view of the wall panel of FIG. 1;

FIG. 6 is a rear elevation view of the wall panel of FIG. 1; FIG. 7 is a top plan view of the wall panel of FIG. 1; and, FIG. 8 is a bottom plan view of the wall panel of FIG. 1. The broken lines in the drawings depict portions of the wall panel for an animal housing unit as shown and described.

1 Claim, 6 Drawing Sheets
